US0D1056697S

(12) United States Design Patent (10) Patent No.: US D1,056,697 S
(45) Date of Patent: * Jan. 7, 2025

(54) FURNITURE FITTING

- (71) Applicant: Julius Blum GmbH, Hoechst (AT)
(72) Inventor: Sarah Scheffknecht, Krumbach (AT)
(73) Assignee: JULIUS BLUM GMBH, Hoechst (AT)
() Term: 15 Years
(21) Appl. No.: 29/882,715
(22) Filed: Jan. 18, 2023

(30) Foreign Application Priority Data

- Jul. 25, 2022 (EM) 9097108-0002
(51) LOC (15) Cl. 08-06
(52) U.S. Cl.
USPC D8/323

(57) CLAIM

The ornamental design for a furniture fitting as shown and described.

DESCRIPTION

FIG. 1 is a perspective view of the furniture fitting;

FIG. 2 is a left side view thereof;

FIG. 3 is a front view thereof;

FIG. 4 is a rear view thereof;

FIG. 5 is a right side view thereof;

FIG. 6 is a top view thereof; and,

FIG. 7 is a bottom view thereof.

The broken lines are for the purpose of illustrating portions of the furniture fitting and form no part of the claimed design.

1 Claim, 7 Drawing Sheets
